[57] CLAIM

The ornamental design for the illuminated game board, as shown and described.

DESCRIPTION

FIG. 1 is a front elevational view of the illuminated game board showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a bottom perspective view thereof.

The two projections shown in broken lines in FIGS. 1 and 2 represent game pieces and are shown for illustrative purposes only, forming no part of the claimed design.
